Primary Examiner — Xavier Marti-Santos

(57) **CLAIM**

The ornamental design for a hairdressing apparatus nozzle as shown and described.

DESCRIPTION

The patent or application file contains at least one drawing executed in color. Copies of this patent or patent application publication with color drawing(s) will be provided by the Office upon request and payment of the necessary fee.

1.Hairdressing apparatus nozzle

1.1 : Perspective

1.2 : Back

1.3 : Bottom

1.4 : Top

1.5 : Right

1.6 : Front

1.7 : Perspective

1.8 : Left

The characteristic elements of the design are featured in the shape of the hairdressing apparatus nozzle as represented. The portions of the hairdressing apparatus nozzle shown with a red transparent overlay depict portions of the hairdressing apparatus nozzle that form no part of the claimed design.

1 Claim, 8 Drawing Sheets
